UNITED STATES PATENT OFFICE.

GUSTAF ENGELBREKT, OF SUPERIOR, WISCONSIN.

AUTOMATIC WIRELESS SIGNAL.

1,265,633.

Specification of Letters Patent.

Patented May 7, 1918.

Application filed June 27, 1916. Serial No. 106,204.

To all whom it may concern:

Be it known that I, GUSTAF ENGELBREKT, a citizen of the United States, residing at Superior, in the county of Douglas and State 5 of Wisconsin, have invented a new and useful Automatic Wireless Signal, of which the following is a specification.

This invention has reference to automatic wireless signals adapted to either large or 10 small vessels and particularly useful on sailing vessels. The object of the invention is to provide an automatic means whereby signals may be sent out and received in alternation during brief or sufficiently prolonged 15 periods to become effective.

In accordance with the present invention there is provided a wireless sending outfit and a wireless receiving outfit, with a controlling switch driven continuously by a 20 suitable source of power to couple up a sending outfit for a brief period of time, and then couple up the receiving outfit for a similar brief period of time, the coupling of the sending and receiving outfits being in 25 alternation. There is also provided an aerial so constructed as to be particularly sensitive to vibrations produced by very faint ether waves.

The invention will be best understood 30 from a consideration of the following detailed description, taken in connection with the accompanying drawings forming part of this specification, with the further understanding that while the drawings show a 35 practical form of the invention, the latter is not confined to any strict conformity with the showing of the drawings, but may be changed and modified so long as such changes and modifications come within the scope of 40 the appended claim.

In the drawings:—

Figure 1 is a diagram of an automatic sending and receiving outfit embodying the present invention.

Fig. 2 is a view of a small vessel equipped with the invention.

Fig. 3 is an elevation partly in section of an automatic switch for alternating the sending and receiving outfits.

Fig. 4 is a section on the line 4—4 of Fig. 3.

Fig. 5 is a plan view of the aerial.

Referring to the drawings there is shown an aerial 1 comprising a frusto-conical coil 55 which may be made of a heavy copper strand composed of many fine copper wires braided

together. Such an aerial is readily supported upon a mast, such as the mast 2 of a vessel 3 shown in Fig. 2, such vessel being a small sailing vessel to illustrate one adaptation of 60 the invention. It will be understood that the invention may be used upon larger vessels than shown in Fig. 2 and may be used upon steam or like vessels instead of sailing vessels. Furthermore, it is quite feasible to 65 use the invention upon other traveling means than water vessels, as, for instance, the invention may be installed upon a locomotive.

The particular character of the conveyance 70 carrying the invention is not of moment, because the salient features of the invention have to do with the wireless side thereof, and not with the conveyance, since it is not even necessary that the invention be 75 installed upon a moving structure.

At some convenient point, say, in the cabin 4 of the vessel 3, there is provided a switch structure 5 comprising a circular series of conducting blocks 6, 7, respectively, 80 in alternation, with the adjacent ends of the blocks separated by insulating fillers 8.

The circular series or ring of blocks 6 and 7 is conveniently mounted upon a support 9 in turn carried by a box or casing 10 inclosing a motor, such as clockworks, indicated by gearing 11, 12, in Fig. 3, the gear 12 being fast to an arbor 13 projecting through the support 9 and within the ring carrying a hub 14 with oppositely disposed spring 90 brushes 15 of such length and so located as to sweep about the inner surface of the conducting blocks 6 and 7 to make contact therewith. Furthermore, the arbor 13 carries contact brushes 16 in diametric relation 95 and arranged to engage the top surfaces of the blocks 6 and 7, assuming these surfaces to be horizontal.

The two sets of brushes 15 and 16 insure 100 good contact and are arranged to bridge diametrically opposite blocks of the series.

Certain of the blocks, say, half of the number of blocks 6 and 7 in regular order, are connected by conductor 17 to a common conductor 18 connected to one end of the 105 aerial 1. The remaining blocks have alternate ones connected to conductors 19 and 20, respectively.

The conductors 19 connect in common to one terminal 21 of an adjustable tuning coil 110 22, the other terminal of which is connected by a conductor 23 to a suitable ground,

which in the case of a vessel is usually the metal sheathing of the vessel, but any other arrangement whereby good electrical contact is established with the water in which the vessel floats may be employed. In the case of a locomotive, the ground will be through the metal parts of the locomotive to the rails, and from thence to the earth.

The tuning coil 22 is provided with the usual sliding coil 24, which latter carries a pointer 25 movable along a scale 26. One terminal of the sliding coil 24 is connected by a conductor 27 to one side of a detector 28 of any approved form, which in turn is connected by a conductor 29 to one side of a relay 30, the other side of which is connected by a conductor 31 to the other terminal of the coil 24. The relay controls a circuit including an audible signal, such as a bell 32, a switch 33, and a battery 34, such battery being representative of any suitable source of electrical energy.

The conductors 20 are connected in common to a helix or oscillation transformer 35 of appropriate form having a ground connection 36 and an adjustable connection through a conductor 37 to one side of an induction coil 38, the other side of which is connected to a spark gap 39 in turn connected to the conductor 36. The spark coil 38 is supplied with current by means of a battery 40 which may be taken as representative of any suitable source of electrical current.

The various devices named, with the exception of the aerial 1 and switch 5, may be such wireless devices as are found upon the market, and which are commonly used in wireless outfits.

The arrangement shown and described will answer very well for most purposes, but, of course, more elaborate outfits may be installed if desired, the present invention having nothing to do with the particular structures of the instruments employed, aside from the aerial 1 and switch 5.

Assuming that the outfit is installed upon a vessel, the clockwork is set in motion and appropriate adjustments are made, whereupon outgoing impulses are sent to the aerial for a brief period of time, say, five or ten seconds, and then for a like period of time the transmitting outfit is cut out and the receiving outfit is included in circuit with the aerial, so that any ether waves which may at the time be passing are caught by the aerial and conditions being right the bell 32 will be caused to ring during the period while the receiving side of the outfit is included in the circuit.

The aerial is of a form making it quite

feasible to mount it upon the top of a single upright, such as the mast of a boat having but one mast, or any vessel or vehicle not supplied with two or more spaced points capable of supporting an aerial grid.

While any suitable power unit may be used to drive the bridging brushes or arms of the switch 5, spring-actuated clockwork is one of the most convenient means for the purpose. The switch arms may be mounted on the arbor 13 of the clockwork in various ways. For instance, the hub 14 may be slipped on to the arbor and held in place by a set screw 41 and the end of the arbor beyond the hub 4 may be squared as shown at 42 to receive a similarly squared hub 43 carrying the brushes 16.

Any suitable signal means may be employed on the sending side of the outfit, and it is quite possible to utilize the switch 5 as such a means. For instance, the out-going waves may be tuned to a certain pitch and by regulating the speed of the clockwork the intervals of sending may correspond to some prearrangement, whereby a series of impulses of a certain pitch interspersed by intervals of silence occurring so often may represent a signal peculiar to the vessel carrying the outfit, and be so recognized as a precautionary signal indicating to the listener at some other point the presence of some vessel to be avoided by some other vessel picking up the signals. On the receiving side the same idea is present, but in the case of danger zones along a coast such dangerous conditions will be indicated by special prearranged signals.

What is claimed is:—

A wireless signal system comprising an automatic sending outfit, an automatic receiving outfit, an aerial, and an automatic switch for coupling the respective outfits in alternation to the aerial, said automatic switch comprising an even number of contacts in circular series, with one half of the contacts connected to the aerial and the other half of the contacts connected in alternation to the sending and receiving outfits, said switch being provided with a rotatable bridging member for electrically connecting diametrically opposite contacts in the order of rotation of the bridging member.

In testimony that I claim the foregoing as my own I have hereto affixed my signature in the presence of two witnesses.

GUSTAF ENGELBREKT.
